UNITED STATES PATENT OFFICE.

MIKE WOOSZCZUK, OF ELIZABETHPORT, NEW JERSEY.

MASK.

1,286,476.

Specification of Letters Patent.

Patented Dec. 3, 1918.

Application filed March 23, 1918. Serial No. 224,291.

To all whom it may concern:

Be it known that I, MIKE WOOSZCZUK, a subject of the Emperor of Austria, resident of Elizabethport, county of Union, and 5 State of New Jersey, have invented certain new and useful Improvements in Masks, of which the following is a specification.

This invention relates to improvements in helmets or guards to be used by soldiers and 10 others so as to protect the face and head from bullets.

The principal object of the invention is to provide a helmet or head covering, with a curtain capable of being closely folded or 15 extended for use.

A further object is to provide means combined with the curtain whereby it may be adjusted to any desired height relative to the supporting elements, the curtain itself being 20 substantially resistant to bullets or like projectiles.

These and other like objects are attained by the novel construction and combination 25 of parts hereinafter described and shown in the accompanying drawing, forming a material part of this disclosure, and in which:—

Figure 1 is a perspective view, showing the application of the invention.

Fig. 2 is a vertical sectional view, taken substantially through the center of the same.

Fig. 3 is a fragmentary side elevational view, showing the curtain supporting means.

Fig. 4 is a front elevational view of the 35 curtain shown in a partially coiled or rolled position.

Fig. 5 is a like view of the same, the curtain being extended to its full length, and

Fig. 6 is a fragmentary plan and sectional 40 view of the curtain roller supports, the section being taken on line 6—6 of Fig. 2.

In the drawings the crown of the hat or head covering indicated by the numeral 10, is integrally joined with rim 11, the same 45 being preferably made of bullet proof material. Connected at the junction of the rim with the crown, by foot brackets 14, is a pair of oppositely disposed, downwardly extending guide bars 15, the same reaching 50 to a point substantially level with the bust of the wearer.

These guide bars have inturned flanges 16, at each of their longitudinal edges, while a similar flange 17, extends outwardly to 55 greater distance therebetween and adapted

to engage therewith are wheel bearings 20, the flanged edges 21 of which are fitted to be received within the spaces between the flanges 16 and 17 of the guide bars by which they are guided. These wheel bearings act 60 as bearings for the ends 23, of a cylindrical roller 24, which has upon one of its extending ends a corrugated actuating knob 25, by means of which the roller may be readily rotated. This roller acts as a support for 65 a flexible steel curtain or shield 28, the upper end of which is attached to the roller, and which is formed with horizontal corrugations so as to bend easily, and provided with openings 29 through which a view may be 70 taken, another opening 29 admitting the nose, while the mouth opening 30, is arranged at the lower part of the curtain.

The lower end of the curtain is engaged with a rod or bar 32, which, together with 75 the roller, is held in engagement with the guide bars 15, by means of a pair of spring rods 35, each of which is formed with a plurality of undulating curves or sinuosities extending their full length whereby the 80 curtain may be adjusted, the rods 35 being fixed at their upper ends in the brackets 14 and secured to the lower ends of the guides 15 at their bottom, and it will be obvious that upon actuating the knob 35, the curtain 85 may be rolled upon the roller 24, so that any part thereof may be exposed as may be desired, or the entire length of the curtain may be drawn into operative position. It is also possible to disengage the 90 brackets 14 from the helmet or cap worn by the operator, so that the entire apparatus may be removed or engaged in a ready and convenient manner. It is to be understood that the roller 24 and rod 32 are independently movable up or down within the structure and that the pressure of the spring elements 35 on the roller 24 maintains the wheel bearings 20 in frictional contact with the guides 15, and normally prevents the curtain 100 from unrolling, as the corrugations in rods 35 will only allow a step by step downward movement of the curtain.

Having thus described my invention what I claim as new and desire to secure by Letters Patent, is—

1. In a helmet, the combination with a missile-resistant head covering, a pair of brackets attached at the junction of the rim and crown thereof, recessed bars extending 110

down from said brackets, and a movable curtain of missile-resistant material engaged with said fixed bars.

2. In a helmet, the combination with a head covering comprising a crown and rim, of a pair of guide rods extending downwardly from the junction of said crown and rim, wheel bearings engaged in said guide rods, a roller upon which said wheel bearings are mounted, means for rotating said roller, a rod disposed at the lower end of said supports, a curtain located between said roller and said rod, means combined with said roller whereby said curtain may be raised or lowered, and means for holding said curtain in an adjusted position.

3. In a helmet, the combination with a head covering comprising a crown and rim, of a pair of support bars rigidly engaged at the junction of said crown and rim, a curtain adjustably secured to said support bars,

means for winding said curtain, and a pair of undulating spring elements affixed in front of said support bars whereby said curtain may be held in an adjusted position. 25

4. In a head covering comprising a crown and rim, a pair of support bars rigidly engaged at the junction of said crown and rim, resilient undulating elements secured at their ends to the respective ends of said support bars, a curtain pendant therebetween, pulleys engaging with said support, a roller upon which said pulleys are mounted, said roller being secured in the upper ends of said curtain, and means on said roller for 30 winding said curtain thereupon whereby said curtain may be raised or lowered, said roller being engageable by said undulating elements in any adjusted position. 35

In testimony whereof I have affixed my 40 signature.

MIKE WOLOSZCZUK.
